UNITED STATES PATENT OFFICE.

HENRY J. GILBERT, OF SAGINAW, MICHIGAN.

PULLEY.

No. 840,764.

Specification of Letters Patent.

Patented Jan. 8, 1907.

Application filed July 6, 1903. Serial No. 164,427.

To all whom it may concern:

Be it known that I, HENRY J. GILBERT, a citizen of the United States, residing at Saginaw, in the county of Saginaw and State of Michigan, have invented certain new and useful Improvements in Pulleys, of which the following is a description, reference being had to the accompanying drawings, forming part of this specification.

10 My invention relates more specifically to pulleys constructed of sheet metal, and has for one of its objects the production of a sheet-metal pulley of such construction that a pulley of any desired width of face may be readily built up from uniform spoke-and-hub construction, whereby the provision of differing spoke-and-hub constructions for pulleys of different widths is rendered unnecessary.

Another object of my invention is the provision of more efficient spoke-and-rim connections of sheet-metal pulleys than have heretofore been devised.

A third object of my invention is the provision of novel interchangeable bushings for sheet-metal pulleys.

In the accompanying drawings, Figure 1 is a side elevation of one form of my improved pulley; Figs. 2, 3, 4, and 4^a, detail views of the spoke-and-rim connections of said pulley; Figs. 5, 6, 7, and 8, detail views of modified forms of such spoke-and-rim connections; Figs. 9 and 10, perspective and end views of one form of the novel sheet-metal bushing forming one part of my invention; Fig. 11, an end view of two of the bushings of Figs. 9 and 10 in assembled position and provided with sheet-metal thimbles; and Fig. 12 a perspective view, and Fig. 13 an end view, of a spirally-corrugated sheet-metal bushing for the same purpose as the bushings of Figs. 9, 10, and 11.

The same letters of reference are used to indicate corresponding parts in the several views.

45 In a prior application filed June 9, 1903, Serial No. 160,730, I have illustrated one form of pulley embodying the first feature of my present invention—*i. e.*, a sheet-metal pulley of such construction that a pulley of any desired face may be readily built up from uniform spoke-and-hub construction—but the construction illustrated in said application is designed more particularly for pulleys of small and medium size, and for 55 pulleys of large size I have devised the construction shown in Fig. 1 of the present appli-

cation. In this construction the sheet-metal rim A of the pulley is composed of four segments, each secured at its opposite ends to the outer ends of a pair of spoke-arms B C, 60 projecting at right angles to each other from an integral connecting hub portion D. Each of these spoke-arms B C D is of approximately U shape in cross-section throughout its length, as shown in Figs. 1^a and 4. The 65 arms B B preferably abut tightly together throughout their length while the arms C C are separated a slight distance from each other, excepting at their outer ends, to permit the two halves of the pulley to be clamped 70 upon the shaft by the bolts E E. Similar bolts F F are passed through the arms B B adjacent the hub of the pulley, but in the construction shown these bolts are employed for the purpose of permanently securing said 75 arms together, as are the bolts G G at their outer ends, so that a two-part or separable pulley is formed, separating along the line between the spoke-arms C C. Rim-bolts H H are passed through the arms C C at 80 their outer ends to secure together the meeting ends of the two halves of the rim when placed upon the shaft.

A narrow faced pulley of any desired diameter may be built up in the manner 85 above described with a single set of the four spoke-arms B C D, and when it is desired to construct a pulley of wider face it is simply necessary to select rim-segments having a greater width of face and secure in them a 90 plurality of sets of such spoke-arms side by side. The opposite edges of the rim are preferably rolled into tubular form, as shown in Figs. 1 and 3.

For the purposes of this general construction any suitable spoke-and-rim connection may be employed for securing the outer ends of the spoke-arms to the ends of the rim-segments; but in Figs. 2 to 8 I have illustrated three efficient arrangements of a similar character, but differing specifically from each other, one or another of which will preferably be employed. In Figs. 2 and 3 the meeting ends of the rim-segments are provided with inwardly-bent tongues I I, adapted to abut 100 against each other when the parts of the pulley are placed together, as in Fig. 2. The ends of the spoke-arms C are shaped as shown in Fig. 4 or 5, being provided with cut-away spaces or recesses a a, leaving projecting portions a' a' between said recesses and the ends 105 of the spoke-arms and with end tongues b

bent upward between the opposite sides of the spoke-arms, but of such limited length as to leave a recess *c* above its upper end and between the sides of the spoke-arm corresponding in depth to the recesses *a a*. In Fig. 4^a the end of the spoke-arm is also provided with laterally-projecting tongues or flanges *b'*, adapted to fit against the rim at the opposite side of the middle tongue *b*.

10 The inwardly-bent tongue *I* of the rim-segment in Fig. 3 is of T shape or provided with recesses to receive the projecting portions *a' a'* of the spoke-arm and is shaped to fit in the recesses *a a* and *c* in the spoke-arm, as shown in Fig. 3, so that its upper surface will come flush with the upper edges of the sides of the spoke-arm. The end tongues *b b'* of the spoke-arms are riveted to the rim-segments by rivets *d*, while the ends of the 20 spoke-arms and the meeting ends of the rim-segments are clamped together by the bolts *H*, which pass through the spoke-arms and through the tongues *I I* of the rim-segments, as shown in Fig. 2. The rim connections of the two spoke-arms are alike, as indicated in Fig. 2, Figs. 3, 4, and 4^a showing in detail the connection of the lower one of the two arms. The employment of the side tongues *b'* materially strengthens the connection between the spokes and rim; but where maximum strength is not required they may be omitted, as in Figs. 1 and 4.

The connection shown in Figs. 5 and 6 is similar to that of Figs. 2, 3, and 4, the principal difference being that the tongues *I* of the rim-segments are made considerably wider than the spoke-arms and are provided with openings, through which lugs *e e* upon the edges of the sides of the spoke-arms project, 35 the edges of said spoke-arms being recessed or cut away at their outer ends except for such projecting lugs to receive the tongues *I I* of the rim-segments and to permit them to fit into the spoke-arms. The openings in the 40 tongues *I*, through which the lugs *e* project, are preferably made tapering, and the lugs are swaged out to fill them and lock the tongues to the spokes, as shown. The clamping-bolts *H* pass through the tongues *I*, as in 45 the previous construction, and the spoke-arms may or may not be provided with the end tongues *b b'* of such construction.

In the construction of Figs. 7 and 8, which is otherwise similar to Figs. 5 and 6, the 55 spoke-arms are shown provided with the end tongues *b* and *b'* of the prior construction, all of such tongues being riveted to the rim-segments by rivets *d*.

In Figs. 9 and 10 I have shown a novel 60 construction of interchangeable bushing for pulleys of this character composed of sheet metal stamped into shape to form longitudinally-extending corrugations presenting outer bearing-surfaces *g*, adapted to fit the shaft-opening of the pulley, and inner bearing-sur-

faces *h*, adapted to fit the shaft. The bushings of Figs. 9 and 10 may be applied directly to the shaft, one upon each side thereof, in the shaft-opening of the pulley, and the pulley clamped to the shaft, the outer bearing-surfaces engaging the shaft-opening of the pulley and the inner surfaces *h* bearing directly upon the shaft; but I prefer to strengthen and brace the bushings by securing within them sheet-metal thimbles *i*, such as shown in Fig. 11. If it be desired to key the bushing to the shaft, such sheet-metal thimble may be bent outward into one of the corrugations of the bushing to form a key-way, as shown at *j* in Fig. 11.

In Figs. 12 and 13 I have shown a sheet-metal bushing corresponding to that of Figs. 9, 10, and 11, excepting that its lengthwise corrugations instead of being straight run spirally of it. This bushing may be applied directly to the shaft, as shown, or may have a sheet-metal thimble *i* secured in it, as in Fig. 13.

The bushings of either Figs. 9 and 10 or 12 and 13 are light, efficient, and inexpensive 90 bushings for pulleys of this character. They may be made of any desired uniform length and employed in sets, the number of sets used with each pulley depending upon the width of the pulley.

I am aware that sheet-metal bushings corrugated in circles circumferentially of the shaft have heretofore been employed; but my novel bushings having either straight or spiral corrugations extending lengthwise of 100 the shaft are not only simpler and cheaper to manufacture, but are more efficient, for the reasons, among others, that if the pulley is inclined to slip upon the shaft the circumferential corrugations of the old bushings are 105 apt to wear shallow circumferential grooves in the shaft, and thereby cause the pulley to become looser and looser, whereas with my lengthwise-extending corrugations the bearing-surfaces of the bushing extend its full 110 length, and no such result can follow any slipping of the pulley upon the shaft.

Having thus fully described my invention, I claim—

1. A separable pulley made in four similar 115 parts, each part comprising a sheet-metal rim-segment, a spoke structure formed of a single piece of sheet metal, and consisting of a hub portion and two spoke-arm sections projecting therefrom at right angles to each 120 other and secured at their outer ends to a rim-segment, and means for securing the parts of the pulley together and clamping them upon the shaft; substantially as described.

2. A separable pulley made in four similar 125 parts, each part comprising a sheet-metal rim-segment, a spoke structure formed of a single piece of sheet metal approximately U-shaped in cross-section and consisting of a 130

hub portion D and two spoke-arm sections B C projecting therefrom at right angles to each other and secured at their outer ends to a rim-segment, bolts F G for permanently securing the adjacent arms B B together and thereby forming two separate halves of the pulley, and means for securing such two halves of the pulley together and clamping them to the shaft; substantially as described.

3. A pulley comprising the rim-segments A A having the tongues I I extending inward therefrom at approximately right angles to the surface of the rim and provided with recesses, the sheet-metal spoke-arms C C provided with recesses adapted to receive the tongues I I and with projections fitting in the recesses of said tongues, and means for securing the opposing rim-segments and spoke-arms together; substantially as described.

4. A pulley comprising the rim-segments A A having the inturned tongues I I provided with recesses, the sheet-metal spoke-arms C C provided with the recesses a a for the tongues I I and with the projecting portions a' a' engaging the recesses in the tongues I I, and means for securing the opposing rim-segments and spoke-arms together; substantially as described.

5. A pulley comprising the rim-segments A A having the inturned tongues I I, the sheet-metal spoke-arms C C provided with the end tongues b riveted to the rim-segments A A, and means for securing the opposing rim-segments and spoke-arms together; substantially as described.

6. A pulley comprising the rim-segments A A having the inturned tongues I I, the sheet-metal spoke-arms C C provided with the end tongues b and b' riveted to the rim-segments A A, and means for securing the opposing rim-segments and spoke-arms together; substantially as described.

7. A pulley comprising the rim-segments A A having the inturned tongues I I provided with recesses, the sheet-metal spoke-arms C C provided with recesses for the tongues I I and with projecting portions engaging the recesses in the tongues and with the end tongues b riveted to the rim-segments A A, and means for securing the opposing rim-segments and spoke-arms together; substantially as described.

8. A pulley comprising the rim-segments A A having the inturned tongues I I provided with recesses, the sheet-metal spoke-arms C C provided with recesses for the tongues I I

and with projecting portions engaging the recesses in the tongues and with the end tongues b and b' riveted to the rim-segments A A, and means for securing the opposing rim-segments and spoke-arms together; substantially as described.

9. A pulley comprising the rim-segments A A having the inturned tongues I I provided with recesses, the sheet-metal spoke-arms C C provided with the recesses a a for the tongues I I and with the projecting portions a' a' engaging the recesses in said tongues, and with the end tongues b riveted to the rim-segments, and means for securing the opposing rim-segments and spoke-arms together; substantially as described.

10. A pulley comprising the rim-segments A A having the inturned tongues I I provided with recesses, the sheet-metal spoke-arms C C provided with the recesses a a for the tongues I I and with the projecting portions a' a' engaging the recesses in said tongues, and with the end tongues b and b' riveted to the rim-segments, and means for securing the opposing rim-segments and spoke-arms together; substantially as described.

11. A sheet-metal bushing for pulleys having corrugations extending lengthwise of it and having external bearing-surfaces concentric to the axis of the bushing; substantially as described.

12. A sheet-metal bushing for pulleys having corrugations extending lengthwise of it and having a sheet-metal thimble permanently secured to it within its shaft-opening; substantially as described.

13. A sheet-metal bushing for pulleys having corrugations extending lengthwise of it and a sheet-metal thimble secured in its shaft-opening and bent outward into one of its corrugations to form a keyway; substantially as described.

14. A sheet-metal bushing for pulleys having straight corrugations extending lengthwise of it from end to end and having external bearing-surfaces concentric to the axis of the bushing; substantially as described.

15. A sheet-metal bushing for pulleys having straight corrugations extending from end to end of it and having a sheet-metal thimble permanently secured to it within its shaft-opening; substantially as described.

HENRY J. GILBERT.
